COMBINED LIGHTER AND FLASH LAMP

Yoshio Okada, Tokyo, Japan

Application June 26, 1957, Serial No. 46,742

Term of patent 3½ years

(Cl. D48—27)

FIG. 1.

FIG. 2.

FIG. 3.

FIG. 4.

FIG. 5.

Fig. 1 is a front elevational view of a combined lighter and flash lamp showing my new design;

Fig. 2 is an end elevational view taken from the left of Figure 1;

Fig. 3 is an end elevational view taken from the right of Figure 1;

Fig. 4 is a rear elevation thereof; and

Fig. 5 is a top plan view thereof.

I claim:

The ornamental design for a combined lighter and flash lamp, substantially as shown.
